UNITED STATES PATENT OFFICE.

JOHN H. ANDERSON, OF ST. PAUL, MINNESOTA.

SLED KNEE.

Application filed December 24, 1920. Serial No. 432,957.

To all whom it may concern:

Be it known that I, JOHN H. ANDERSON, a citizen of the United States, resident of St. Paul, county of Hennepin, State of Minnesota, have invented certain new and useful Improvements in Sled Knees, of which the following is a specification.

The object of my invention is to provide a malleable knee which will allow the sled to be taken apart upon the removal of bolts.

A further object is to provide a knee which provides for the support of the sled beam without the necessity of rigidly securing the beam to the runner.

15 A further object is to provide improved bearings for the knee at the top and bottom of the beam and also improved means for mounting the knee of the runner.

The invention consists generally in various constructions and combinations, all as hereinafter described and particularly pointed out in the claims.

In the accompanying drawings forming part of this specification,

25 Figure 1 is a side elevation of a sled runner with my improved knee applied thereto, Figure 2 is a perspective view showing the position of the knee on the runner,

30 Figure 3 is a transverse sectional view through the runner,

Figure 4 is a plan view with the strap or rave iron removed,

In the drawing, 2 represents a sled runner of any ordinary or preferred construction. 3 is the base of the knee, made preferably of malleable iron and having depending flanges 4 which extend down on each side of the runner, as shown plainly in Figure 3. Holes 5 are provided in the base through which screws may be inserted into the runner. Upright standards 6 are formed on the runner, having brackets 7 and flanges 8 at the top provided at the ends with holes 9. The standards 6 flare slightly from the bottom upwardly and between them the end of the sled beam 10 is seated. This beam is provided at the top and bottom with transverse grooves 11 and beam iron plates 12 and 12^a are arranged respectively above and below the beam and are provided with ribs 13 which fit into the grooves 11 in the beam, as shown plainly in Figure 3. The plates 12 and 12^a also have recesses 14 which receive the upright standards 6 which are preferably rounded, as shown in Figure 2, to fit snugly into the recesses 14 of the beam

irons. The irons are held in place preferably by means of bolts 15 which have their heads seated on flanges 16 of the base 3 and project up through holes in the beam and have lock nuts 17 for securing the plates 12 and 12^a and the beam together. The plate 12 has holes to receive the upper ends of the bolts 15 and when the lock nuts 17 are tightened, the beam iron plates and the beam will be firmly secured together without, however, being rigidly connected with the base of the knee on which the beam is seated. This construction allows for relative movement of the runner and beam and provides for an easier running sled than where there is a rigid connection between the beam and the runner. A slight flare of the standard 6 permits rocking of the runner and the beam in the operation of the sled under a load.

The beam is held between the standards of the knee by suitable means, preferably a curved rave iron strap 19 that is formed to extend across the beam with its ends resting upon the flanges 8, bolts 20 being provided for securing the strap to said flange. A space is provided between the middle portion of the rave iron and the beam to allow freedom of movement of the beam. When the parts are assembled, the knee will correspond to the view in Figure 1, where the strap 19 is shown extending between the upper ends of the bolt 15, and resting upon the flanges 8. The plate 12, as well as the one at the bottom, has lugs 21 formed on each side near the recess 14 to lap by and embrace the corners of the beam and grip it firmly when the bolts 15 are tightened.

I claim as my invention:

1. The combination, with a sled runner, of a knee having a base seated on the top of the runner and provided with depending flanges upon each side of the runner, standards projecting upwardly from said base, a beam fitting between said standards and seated on said base, plates fitting the upper and under surfaces of said beam and having recesses therein to receive said standards, bolts passing vertically through said plates and through said beam and securing them together, the engagement of said standards with the walls of said recesses preventing endwise movement of said beam, and means bridging the space between said standards above said beam for holding said beam between said standards.

2. The combination, with a sled runner,

of a knee seated thereon and comprising a base portion having vertical flanges to straddle said runner and laterally projecting horizontal flanges and a pair of upright standards, a bolster having its end fitting between said standards, a lower plate seated upon said laterally projecting flanges and interlocking with the underside of said bolster, an upper plate interlocking with the 10 upper surface of said bolster, bolts passing through said bolster for securing said plates together, said plates having means co-operating with said standards to prevent longitudinal movement of said bolster, and a 15 plate secured to the upper portions of said standards and bridging the upper plate on said bolster and spaced therefrom.

3. The combination, with a sled runner, of a knee seated thereon and having upwardly 20 projecting diverging standards, a bolster having its end fitting between said standards and provided in its upper and under surfaces with narrow transverse grooves, a plate seated in said knee between said standards 25 and having an upwardly projecting rib fitting the groove in the underside of said bolster, a second plate seated on the upper surface of said bolster and having a rib fitting the groove therein, and bolts passing 30 through said plates and said bolster and securing them together, said plates projecting beyond said bolster on each side and having recesses to receive said standards and allowing said bolster to rock between said 35 diverging standards, and a strap secured to the upper portions of said standards and bridging said bolster.

4. The combination with a sled runner, of a knee mounted thereon, and comprising a 40 base portion adapted to be seated on the top of the runner and having flanges to depend upon each side of the runner, said base portion having upwardly projecting integral

standards and braces therefor, said standards having rounded opposing faces and 45 provided at their upper ends with elongated bearing surfaces in alignment substantially with said runner, a bolster having its end fitting between said standards and provided in its upper and under surfaces with comparatively narrow transverse grooves, a 50 plate seated on said knee between said standards and having an upwardly projecting rib fitting the grooves in the under side of said bolster, a second plate seated on the 55 upper surface of said bolster and having a rib fitting the transverse groove therein, said plates projecting outwardly beyond the vertical faces of said bolster and having recesses therein to receive the curved portions 60 of said standards, bolts passing vertically through said bolster upon opposite sides of said grooves and through said plates for securing them on said bolster, and a strap 65 bridging said second plate and having its end portions seated on the bearing surfaces of said standards and secured thereto.

5. The combination with a sled runner, of a knee having a base seated on the top of said runner, standards projecting upwardly from 70 said base, a beam fitting between said standards and seated on said base, plates fitting the upper and under surfaces of said beam, and having recesses therein to receive said standards, bolts passing vertically through 75 said plates and through said beam and securing them together, the engagement of said standards with the walls of said recesses preventing endwise movement of said beam, and means bridging the space between said 80 standards above said beam for holding said beam between said standards.

In witness whereof, I have hereunto set my hand this 20th day of December 1920.

JOHN H. ANDERSON.
